ABRADING TOOL

Paul J. Greulach, Fort Wayne, Ind., assignor of
one-half to William E. Platt, Fort Wayne, Ind.

Application February 20, 1946, Serial No. 648,841

7 Claims. (Cl. 51—190)

1

This invention relates to new and useful improvements and structural refinements in abrading machines, more particularly, to a machine such as may be employed for the sanding, dressing, surfacing, or refinishing of floors and the like.

The principal object of the invention is to provide a device of the character herein described in which a unique structure is employed for the mounting of the abrasive medium upon the drum and in which novel means is incorporated for the mounting of the drum itself.

By virtue of the above outlined construction, the span of life of the abrasive medium is considerably lengthened and when the same becomes excessively worn, the replacement thereof may be easily and conveniently effected.

A further advantage resulting from the novel construction of the machine resides in the manner in which the same is used, it being possible to bring the machine within very close limits to the junction of the floor with a wall, so that subsequent edging operation such as was conventionally required, is no longer necessary.

A further object of the invention is to provide such abrading machine with self-contained means for collecting dust and the like, resulting from the abrading operation.

An additional object of the invention is to provide an abrading machine which is pleasing in appearance and which will surpass the general utility and efficiency of machines conventionally employed for the purpose to which it appertains.

With the above more important objects in view, and such other objects as may become apparent as this specification proceeds, the invention consists essentially of the arrangement and construction of parts as illustrated in the accompanying drawings, in which:

Figure 1 is a side elevation of the invention, with the removable cover on the housing thereof in the open position to reveal the construction of the abrading drum.

Figure 2 is a cross-sectional view, taken approximately in the plane of the line 2—2—2—2 in Figure 1.

Figure 3 is a top plan view of a sleeve used in the invention, and

Figure 4 is an end view, partially broken away, of the same.

Like characters of reference are used to designate like parts in the specification and throughout the several views.

Referring now to the accompanying drawings in detail, the invention consists of a housing 10,

2

configured substantially as shown and provided in the bottom thereof with a mounting plate 11, on which an electric motor 12 may be conveniently secured.

5 The housing is also provided with a pivoted handle 13 and with a plurality of wheels 14, whereby the machine as a whole may be conveniently pushed or pulled along the floor 15.

A stationary spindle 16 is formed at one of 10 its ends with a mounting flange 17 and a plurality of bolts 18 are used to secure the flange and the associated spindle to the side 19 of the housing 10.

The spindle 16 is provided with a pair of anti-friction bearings such as the ball bearings 20, the latter in turn, being positioned in an axial bore 21 formed in one end of the abrading drum 22. In this manner, the drum is rotatably mounted on the spindle 16 and it will be noted that 20 the remaining end of the drum is formed with a frusto-conical recess 23 in communication with the bore 21.

The remaining end of the spindle 16 is provided with a screw-threaded portion 24 adapted 25 to receive the nut 25, whereby the drum 22 is retained on the spindle.

Defining the outer surface of the drum 22 is a tapered lateral wall 26, and an expansible sleeve 27 provided with a co-acting, tapered inner wall 30 28 is removably positioned on the drum, as will be clearly apparent from the accompanying drawings.

The sleeve 27 is formed with a plurality of 35 longitudinally extending slots 29, the same being open alternately at the opposite ends of the sleeve, as is best illustrated in the accompanying Figure 3. A tubular abrasive covering such as may assume the form of a continuous sand paper jacket 30, is removably positioned on the sleeve 27 to 40 provide the abrading surface.

A circular anchor plate 31 is secured in the recess 23 of the drum 22, the plate being formed with a screw-threaded aperture 32, concentric with the bore 21. A frusto-conical pressure plate 45 33 is formed at the minor end thereof with the end wall 34, the latter in turn, being formed with a central aperture 35.

The shank of an adjusting screw 36 engages the aperture 32 of the plate 31, and the screw 36 50 is also provided with a shoulder 37 formed with an annular groove 38. The edges of the aperture 35 engage the groove 38, as will be clearly apparent from the accompanying Figure 2, and it should be understood that to facilitate construction, the shoulder 37 may assume the form of an 55

annular ring and that a separate collar 39 may be positioned on the shank of the screw 36 to cooperate with the ring 37 in the formation of the groove 38.

The remaining, that is the major end of the pressure plate 33 carries an out-turned flange 40 and a plurality of off-set brackets 41 are bolted to this flange by means of the bolts 42.

This flange together with the brackets, constitutes means for connecting the pressure plate 33 to the major end of the sleeve 27, the latter being provided for this purpose, with a plurality of inwardly projecting lugs 43. These lugs are receivable between the flange 40 and the brackets 41 and it will be apparent that by loosening the bolts 42 and turning the brackets 41 out of engagement with the lugs 43, the plate 33 may be detached from the sleeve 27.

To facilitate installation and removal of the sleeve 27 and the associated covering 30, the housing 10 is provided with a substantially circular opening 44, normally closed by a hinged cover 45. The latter is pivotally attached to the housing by means of the bolt or rivet 46 and is also provided with a hook-like catch 47. When the cover is in the closed position, the catch 47 engages a securing bolt 48.

Extending transversely across the full width of the drum 22 is a dust pick-up scoop 49, the mouth 50 of the latter being disposed adjacent to the periphery of the drum and slightly above and behind the line of contact of the drum with the floor 15.

The scoop 49 is connected by means of the duct 51 to the inlet of a scroll casing 52. A conventional blower fan 53 is rotatable in this casing, being positioned on the armature shaft of the aforementioned motor 12. The outlet 54 of the casing 52 protrudes out of the housing 10 and a conventional dust collecting receptacle (not shown) may be connected thereto, to accommodate the accumulating dust.

The major end of the drum 22 is formed integrally with a grooved pulley 55, the same in effect, assuming the form of a simple groove provided in the outer wall of the drum. A relatively smaller pulley 56 is positioned on the armature shaft of the motor 12 and an endless belt 57 connects the two pulleys to effect the rotation of the drum.

Having thus described the construction of the invention, its method of operation will now be presented.

In operation, the machine is used in the conventional manner by being pushed or pulled along the floor 15 while the rotating drum 22 provided with the abrasive covering 30 contacts the floor. Simultaneously, the associated fan 53 will draw the dust through the scoop 49 and discharge the same through the duct 54, thereby eliminating the conventionally experienced, undesirable dissipation of dust particles while the machine is in operation.

The essence of the invention resides in the mounting of the drum upon the spindle 16, for it will be noted that since the spindle is secured only at one end thereof to the housing 10, the relatively opposite end of the drum 22 has been extended almost to the inner surface of the housing wall 58. In this manner, the machine may be brought within very close limits to the junction of the floor with a wall, thereby eliminating all subsequent edging operations.

The essence of the invention further resides in the novel manner in which the abrasive covering 30

30 is positioned on the drum, the same being presently described.

Assuming the device to be in the position indicated in Figure 2, by rotating the screw 36, the sleeve 27 together with the covering 30 will be drawn from the tapered surface 26 of the drum 22. The presence of the slots 29 provide for inherent resiliency in the sleeve 27 so that as the sleeve is removed from the drum, the same (the sleeve) will contract so that the covering 30 may be easily removed therefrom.

After the covering has been replaced, the sleeve is again positioned on the drum and by tightening the screw 36, the co-acting tapered surfaces 26 and 28 will uniformly expand the sleeve 27, so that the covering 30 will be firmly and securely retained thereon.

The depth of cut, so to speak, of the abrading drum on the floor may be varied by exerting upward or downward pressure upon the handle 13, the wheels 14 acting as pivots for the housing 10.

The advantage of the continuous surface of the abrasive covering 30 can be readily appreciated, since the same entirely eliminates the flat spot on the drum where the ends of a conventional abrasive strip are secured thereto.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. An abrading drum structure comprising in combination, a drum formed with an axial bore and having a tapered lateral wall defining the outer surface thereof, a stationary spindle in one end of said bore, anti-friction bearings on said spindle, said drum being rotatable on said bearings, an expansible sleeve provided with a co-acting, tapered inner wall, tubular abrasive covering removably positioned on the outer lateral wall of said sleeve, said sleeve being removably positioned on said drum, and means in the remaining end of said bore for applying and removing said sleeve.

2. The device as defined in claim 1 in which said sleeve is formed with a plurality of longitudinally extending slots, each of said slots being open at one of its ends.

3. The device as defined in claim 1 together with a grooved drive pulley formed integrally at one end of said drum.

4. The device as defined in claim 1, in which said means comprises in combination, an anchor plate in said bore, an adjusting screw co-axial with said bore and threaded into said plate, said screw being formed with an annular groove, a pressure plate formed with a central aperture, and connected to said sleeve, the edge of said aperture engaging said groove.

5. A drum structure for abrading machines comprising in combination, a drum formed with an axial bore in one end thereof and with a frusto-conical recess in its remaining end, said recess constituting a continuation of said bore, said drum having a tapered lateral wall defining the outer surface thereof, a stationary spindle in said bore, anti-friction bearings on said spindle, said drum being rotatable on said bearings, an anchor plate in said recess, said plate being formed with a screw-threaded aperture concentric with said bore, a frusto-conical pressure plate, an end wall formed with a central aperture at the minor end

of said pressure plate, an out-turned flange at the major end of said pressure plate, a screw-threaded adjusting bolt engaging said aperture in said anchor plate, a shoulder medially the length of said bolt and an annular groove in said shoulder, the edge of said aperture in the end wall of said pressure plate rotatably engaging said groove, an expansion sleeve provided with a co-acting, tapered inner wall and with a plurality of longitudinally extending slots, said slots being open alternately at the opposite ends of said sleeve, a tubular abrasive covering removably positioned on said sleeve, and separable means for attaching the major end of said sleeve to said flange.

6. The device as defined in claim 5, in which said means comprises in combination, a plurality of inwardly projecting lugs on the inner wall of said sleeve, a plurality of off-set brackets bolted to said flange, said lugs being receivable between 20 said flange and said brackets.

7. The device as defined in claim 5, together with a mounting flange at one end of said spindle and a screw-threaded portion at the remaining end thereof, a nut on said screw-threaded portion for retaining said drum in position, and a grooved drive pulley formed integrally at the major end of said drum.

PAUL J. GREULACH.
